UNITED STATES PATENT OFFICE.

FREDERICK G. GRUEN, OF CINCINNATI, OHIO, ASSIGNOR TO THE D. GRUEN SONS & COMPANY, OF CINCINNATI, OHIO, A CORPORATION OF OHIO.

DESIGN FOR A WRISTBAND-CLASP.

57,641.

Specification for Design. Patented Apr. 26, 1921.

Application filed October 20, 1920. Serial No. 418,333. Term of patent 14 years.

To all whom it may concern:

Be it known that I, FREDERICK G. GRUEN, a citizen of the United States of America, and resident of Cincinnati, in the county of Hamilton and State of Ohio, have invented a new and original and ornamental Design for a Wristband-Clasp, of which the following is a specification, reference being had to the accompanying drawing, forming part thereof.

The figure is a plan view of a wrist-band clasp showing my new design.

I claim:—

The ornamental design for a wrist-band clasp as shown.
